Primary Examiner — Lucy Lieberman(74) *Attorney, Agent, or Firm* — Howard Natter; Natter & Natter(57) **CLAIM**

The ornamental design for a chronograph, as shown and described.

DESCRIPTION

FIG. 1 is a front right side perspective view of a chronograph showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a front and right side perspective view of the chronograph shown in an alternate position.

The broken-lines in the drawings are used to show portions of the chronograph that do not form part of the claimed design.
